UNITED STATES PATENT OFFICE.

FRED WILLIAM STEIN, OF ATCHISON, KANSAS.

RADIO INTERFERENCE ELIMINATOR.

Application filed April 30, 1925. Serial No. 27,118.

This invention relates to devices for perfecting and clarifying the reception of radio signals, and more particularly to a novel device for eliminating interference from undesired stations and also to a noticeable extent reducing the interference caused by discharges of static electricity into the receiving set.

To that end the invention contemplates as its primary object the provision of a simple, practical and reliable device having novel features of construction which enhance its value from a manufacturing standpoint and also facilitates its installation and manipulation.

Another object of the invention is to provide a device which may be included in the antenna circuit and comprises an absorption circuit for extracting the interfering oscillations from the antenna circuit, thus effectually dampening the undesirable oscillations therein.

A further object of the invention is to provide a device of the character set forth which may be used in connection with any type of radio receiving apparatus.

With the above and other objects in view which will more readily appear as the nature of the invention is better understood, the same consists in the novel construction, combination and arrangement of parts hereinafter more fully described, illustrated and claimed.

A preferred and practical embodiment of the invention is shown in the accompanying drawings, in which:—

Figure 1 is a perspective view of the present device.

Figure 2 is a horizontal sectional view thereof.

Figure 3 is a cross sectional view taken at right angles to Figure 2.

Figure 4 is a detail bottom plan view of the device.

Figure 5 is a diagrammatic view showing the circuits involved.

Similar reference characters designate corresponding parts throughout the several figures of the drawings.

According to the embodiment of the invention shown in the accompanying drawings the same preferably includes a base 1 having a chamber or compartment 2 opening at the bottom side thereof and closed by an insulating cover 3, the said cover being secured to the base in any suitable manner, as by nails or tacks. The upper side of the base 1 is provided with a hub 4 having the radial spokes 5 for supporting a "spider-web coil" designated generally as S and including the two inductance windings S' and S². Between the hub 4 and the top of the base 1 there is provided a concealed interiorly threaded nut 6 whose threaded opening aligns with the registering openings 7 and 7^a respectively in the hub and the base. The said nut 6 is adapted to receive a headed micrometer-screw 8 whose upper end is fitted with a manipulating knob 9. The lower headed end of the screw 8 is adapted to bear against an insulation sheet 10 which overlies a condenser designated generally as C and housed in the chamber 2.

The said condenser C preferably consists of a plurality of elongated metal plates 11 of longitudinally arched formation arranged in alternate relation with the mica or equivalent dielectric members 12. The metallic condenser plates 11 are provided with the terminal end portions 13 whereby the ends 14 of the inductance winding S² of the coil S may be attached thereto.

The said base 1 also carries therewith the binding terminals 15 and 16 which connect with the primary winding S' of the spider web coil S, and are also adapted to connect respectively with the lead-in wire from the aerial and the relatively short lead wire to the aerial binding post of the set.

As will be observed from the diagram in Figure 5, the present device includes a tunable circuit S²—C suitably coupled by a coil S' to the collector or pick-up circuit A of the receiving system. The tuned circuit S²—C consists of the fixed inductance S² and a variable capacity C, having the micrometer screw adjustment, while a second inductance S' connected in the pick-up circuit is placed in inductance relation to the first mentioned inductance, both of which are wound on the same form or support 4—5.

The operation of the device is as follows:

The circuit S²—C is tuned to the frequency of the interfering signal. The circuit of which coil S' is a part, is tuned to a different frequency but is set into oscillation by the interfering signal, due to shock excitation. The absorption circuit S²—C, extracts the interfering oscillations from the S' circuit as fast as they are produced, thus effectively damping the undesirable oscillations in the S' circuit. The S²—C circuit, being

out of resonance with all other frequencies, has no effect on the desired signal.

In connection with the coil system S, including the inductance windings S' and S² is wound in the approved fashion, being air spaced and employing a dry wood frame. It consists of two inductances, one of which (S²) is connected to the small brass plate and mica condenser C, the other (S') being connected to the pick-up system. This condenser C, being very small in size, has very low losses, the skin effect in particular being of little consequence. The outer plates are shaped in such a manner that normally the spacing between all of the plates is relatively great. However, when the micrometer screw is turned, the plates are compressed between the headed end of the screw 8 and the wall 3 which acts as an abutment thus reducing the spacing and increasing the capacity of the condenser. In this manner the most precise adjustment is obtained.

The present construction provides an assembly which results in a very compact unit, having the shortest possible leads, and the lowest losses consistent with practicability of manufacture. The device is also useful in connection with any type of radio receptor, the induction coil S' being placed in the antenna circuit of the electro-static type of receiver, or in the loop circuit of a magnetic-type receptor.

The present construction also provides as a distinctive feature, an efficient inductance coupled with a micrometrically controlled capacity which are combined into a practical unit that has a wide range of utility in radio reception.

Without further description it is thought that the features and advantages of the invention will be readily apparent to those skilled in the art, and it will of course be

understood that changes in the form, proportion and minor details of construction may be resorted to, without departing from the spirit of the invention or scope of the appended claims.

I claim:

1. An interference eliminator for radio apparatus including an insulating base having a chamber opening at its bottom side, a cover for the bottom side of the base, a variable condenser consisting of arched spring metal plates and mica dielectric members alternately arranged and spaced apart, a spider-web coil mounted on top of the base and including a hub portion affixed centrally to said base, a nut element concealed between the hub and the top of the base and having a threaded opening registering with corresponding openings in the hub and base, a micrometer screw engaging the threaded opening of the nut and having an exterior manipulating knob whereby the screw may be moved to compress and release the plates of the condenser thereby to vary its capacity.

2. An interference eliminator for radio apparatus including an insulating base, a variable condenser carried by said base and consisting of arched spring metal plates and dielectric members alternately arranged and spaced apart, a coil mounted on said base and including a hub portion fixed to said base, a nut having a threaded opening registering with corresponding openings in the hub and base, a micrometer screw engaging the threaded opening of the nut and having an exterior manipulating knob whereby the screw may be moved to compress and release the plates of the condenser thereby to vary its capacity.

In testimony whereof I hereunto affix my signature.

FRED WILLIAM STEIN.
